UNITED STATES PATENT OFFICE.

WILLIAM FRANKLIN CLAYTON, OF CULLMAN, ALABAMA.

ROLLER-FENDER.

1,377,115.

Specification of Letters Patent.

Patented May 3, 1921.

Application filed September 22, 1919. Serial No. 325,521.

To all whom it may concern:

Be it known that I, WILLIAM F. CLAYTON, citizen of the United States, residing at Cullman, in the county of Cullman and 5 State of Alabama, have invented certain new and useful Improvements in Roller-Fenders; and I do hereby declare the following to be a full, clear, and exact description of the invention, such as will enable others skilled in the art to which it 10 appertains to make and use the same.

This invention relates to plow fenders and particularly to rotary fenders therefor and means for attaching the said rotary fenders.

15 An object of this invention is to provide a means for quickly and simply attaching and detaching a roller fender and especially to also provide a means of utilizing the common means of attachment of a scratcher 20 to a plow for the purpose of attaching a roller fender to a plow.

With these and other objects in view the invention consists of the construction, combination and the detail and arrangement of 25 parts as hereinafter more fully described and claimed.

In the drawings:

Figure 1 is a side elevation of a plow with a fender attachment.

30 Fig. 2 is a perspective of a fender attachment strap.

Fig. 3 is a perspective of attachment device 3 in Fig. 1.

Fig. 4 is a section through a roller fender 35 with a mount attachable to strap 2, strap 2 being shown in sections.

Fig. 5 is a perspective of an attachment to strap 2 where it may be desired to utilize a double set of roller fenders.

40 Figs. 6 and 7 are a side elevation partly broken away of a scratcher showing a fender attached to a scratcher and illustrating how strap 2 can be substituted into a means for attaching the scratcher.

45 In detail, the invention comprises a strap 2 attached to an attachment member 3, the said strap 2 perforated at 4 with a bolt 5 adapted to pass through the said perforation. A clamp 6, conforming to the con-

tour of strap 2 and adjustably mounted in 50 a slot 7, co-operates with the adjustment of bolt 5 in a slot 8 to properly govern the relative angularity of the said fender to the said attachment means. The attachment member 3 is affixed to a plow beam 9 by 55 a clamp 10. Slidably mounted on the strap 2 is a clamp 11, clamp 11 being mounted upon an L shaped member 12 having a support for a stud shaft 13 which carries a roller fender 14. Where two roller fenders 60 are desired to be used a clamp 11^a is perforated as at 13^a and 13^b to support a pair of said shafts 13.

Where it is desired to attach a roller fender of this character to a scratcher, the 65 scratcher spring strap 15 can be removed and a bolt 16 utilized for the same purpose as bolt 5, and clamp 17 can be utilized for the same purpose as clamp 6, thus rendering the said scratcher spring strap inter- 70 changeable with the said strap 2, or if desired, the scratcher strap itself can be utilized for supporting the said fender.

By this simple interchangeable device it 75 is obvious that the construction is very much simplified for mounting the said fenders to devices in common usage.

What I claim is:

In an interchangeable attachment for earth working implements, a fender member, a fender supporting means comprising a depending portion to which the fender member is attached, and a lateral portion at the upper end of said depending portion; and a binding clamp carried by said lateral portion, said binding clamp being constructed and designed to embrace and be frictionally clamped, interchangeably, to a flat metallic bar of a standard earth scratcher, or to a bar of like dimensions 85 attached to a plow or other earth working implement.

In testimony whereof I affix my signature in presence of two witnesses.

WILLIAM FRANKLIN CLAYTON.

Witnesses:

ALBERT G. BAIN,
WILLIAM E. JAMES.
